(57) **CLAIM**

The ornamental design for a projector lamp unit for vehicle, as shown and described.

DESCRIPTION

FIG. 1. is a front perspective view of the front, right, and top sides of a projector lamp unit for vehicle showing our new design;

FIG. 2. is a front view thereof;

FIG. 3. is a rear view thereof;

FIG. 4. is a left side view thereof;

FIG. 5. is a right side view thereof;

FIG. 6. is a top plan view thereof;

FIG. 7. is a bottom plan view thereof; and,

FIG. 8. is a reference view showing a usage state.

The broken lines shown illustrate portions of the projector lamp unit for vehicle in which the design is embodied and form no part of the claimed design.

1 Claim, 8 Drawing Sheets
